UNITED STATES PATENT OFFICE

JOSEPH COOPER, OF NEW YORK, N. Y.

SLIDE FOR EXTENSION TABLES

Application filed November 6, 1930. Serial No. 493,777.

The object of the present invention is to provide a slide for automatic extension tables, the slide so controlling the outer leaves, employed in conjunction with a fixed 5 centre leaf, that upon the outward movement of one underlying leaf the slide will act to carry the second leaf outwardly and the two upwardly to the plane of the centre leaf, a final and reverse movement carrying 10 the movable leaves into contact with the stationary leaf.

The invention particularly relates to the means for controlling cam action of the slides so that when the table is extended and it is 15 desired to contract the table by restoring the movable leaves to their position underlying the centre leaf, such action may readily be effected.

The invention will be described with reference to the accompanying drawings, in 20 which

Fig. 1 is a transverse section through a table in which the slides are incorporated showing the position of the elements when 25 the table is contracted and the movable leaves are lying under the stationary leaf, certain parts of the table being broken away.

Fig. 2 is a plan view, partly broken away, showing the leaves in contracted position and 30 also in the position of the cross sectional view, Fig. 6.

Fig. 3 is a view similar to Fig. 2 showing the table extended and the movable leaves in contact with the fixed centre leaf.

35 Fig. 4 is a horizontal fragmentary section on the line 4—4, Fig. 1.

Fig. 5 is a vertical section on the line 5—5, Fig. 4.

Fig. 6 is a transverse section of a table 40 embodying the invention showing the parts in position after the movable leaves have been carried outwardly preliminary to bringing them into contact with the centre leaf in the plane of the latter.

45 Fig. 7 is an enlarged view similar to Fig. 6 showing the position of the parts when the table is extended and the movable leaves in contact with the centre leaf.

Fig. 8 shows the position of the elements 50 when, after table has been extended, the mov-

able leaves have been moved outwardly and certain switch elements have been actuated to the point where a reverse movement of the movable leaves will carry them down from the plane of the centre leaf to a position below the latter. 55

Fig. 9 is a fragmentary view, partly in section, showing the construction of the switch mechanism.

Fig. 10 is a perspective view of certain 60 elements of the switch mechanism.

Fig. 11 is a fragmentary horizontal section on the line 11—11, Fig. 10.

Referring to Fig. 2 of the drawings, it will be seen that the embodiment of the invention herein illustrated is applied to a table having a stationary centre leaf 1 mounted on two sets of blocks 2, each set being mounted on a horizontal frame member 3 which serves as a support for the slides 4 and 5. Each of 70 these slides is formed with a rack 6, the racks of the opposed slides 4 and 5 being engaged by a pinion 7. Slide 4 at each end of the table may carry a movable leaf 8 and slide 5 at each end of the table may carry a movable 75 leaf 9. Leaf 8 may be provided with a longitudinal apron 8x and leaf 9 may be provided with a longitudinal apron 9x. The slides 4 and 5 are alike in construction and a description of one will suffice for the second. The 80 horizontal frame member 3 is, as to function, the stationary member of the slide construction comprising the slides 4 and 5. To this end at each side thereof frame member 3 is cut with a longitudinal channel 3x to receive 85 a slide bar 10 provided with anti-friction rollers 11 for free running in the channel, the slide bar in each case also carrying a headed stud 12 entering cam slot 13 formed in the slide member now being described, to wit, 4. 90

The bar carries a second headed stud 14 entering a cam slot 15 formed in the said slide member 4, the cam slots 13 and 15 being identical. At one end of the channel 3x is a pin 16 which serves as a stop against any but 95 predetermined movement of bar 10 toward the pin.

Now assuming the parts to be in position of Fig. 1, it will be seen that an outward movement of leaf 8 will, assuming bar 10 to 100

be stopped against movement to the right, cause the said leaf 8 to be carried beyond the right margin of stationary leaf 1. At such point the downwardly extending legs of cam 5 slots 13 and 15 will come into contact with the studs 12 and 14, the said studs will act to carry leaf 8 upwardly to the plane of the stationary leaf. Inward movement of the leaf 8 would simply carry it back to initial 10 position underlying the stationary leaf were it not for the provision of certain stop and switch members now to be described.

Pivottally mounted on slide member 4 at 17 is a stop bar 18 the latter normally being 15 thrown in such position that its active end obstructs the downwardly extending portion of cam slot 13 of the said slide member 4. Stop bar 18 has an outwardly bent end 18a in register with the cam surface 20a of a sliding member 20 suitably held upon member 4 as by a loop piece 21. Switch member 20 pivotally carries a tooth 22 normally held in the position of Fig. 10 by a spring 23. The left hand edge of tooth 22 (in the position 25 of Fig. 10) is bevelled.

When slide 14 is moved from the position shown in Fig. 1 to the position shown in Fig. 6 the leaf 8 will be brought beyond the marginal edge of the stationary leaf 1 and 30 then raised by the action of studs 12 and 14 on the cam faces of the slide formed by cutting the cam slots 13 and 15. In the final outward movement of slide 4 stud 12 will ride over the top of stop 18 and will depress 35 the end of the latter whereupon spring 19 will snap the stop back into position to obstruct the cam slot 13 as shown in Figs. 6 and 7. Slide 4 with leaf 8 may then be moved inwardly in a straight line inasmuch 40 as the slide will be locked to slide bar 10. When, however, slide 4 is moved outwardly from the position shown in Fig. 7 to the position shown in Fig. 8, tooth 22 will come into contact with finger 24 and inasmuch 45 as tooth 22 normally rests against a stop 22a, Fig. 11, the switch device is caused to move bodily to the left until its cam surface 20a swings pivoted stop 18 to position shown in Fig. 8, and the switch member 50 remains in that position while movable leaf 8 with slide 4 is moved to the left causing descent of the leaf to initial closed position as shown in Fig. 1. In its movement from the position shown in Fig. 1 to the position 55 shown in Fig. 6, the tooth 22 passes under finger 24 and thence is carried to a plane intersecting the finger as shown in Fig. 6. When the slide 4 is moved from the position of Fig. 6 to Fig. 7 the bevelled edge of the 60 tooth enables it to be idly swung back, by the finger until it clears the latter and assumes the position shown in Fig. 7. When, however, slide 4 is moved to position of Fig. 8 the tooth 22 will be caused to engage the 65 finger and the switch will be actuated to

swing stop 18 out of engagement with roller 12, as hereinbefore specified.

Having described my invention, what I claim and desire to secure by Letters Patent is as follows:

1. An automatic extension table comprising a centre leaf and leaves adapted to lie under the centre leaf a slide combination for the underleaves comprising a centre slide member, movable slide members adjacent the centre slide member, rack and pinion connections intermediate the movable slide members, cam surfaces carried by the movable slide members, stud carrying members having studs engaging said cam surfaces and permitting relative movement between the slides and said stud carrying members during a movement of an underlying leaf outwardly into the plane of the centre leaf, a member adapted to automatically lock together a slide and its co-acting stud carrying member, a movable switch device adapted to throw said locking member to inactive position, and means for actuating said switch device. 90

2. An automatic extension table comprising a centre leaf and leaves adapted to lie under the centre leaf a slide combination for the underleaves comprising a centre slide member, movable slide members adjacent the centre slide member, rack and pinion connections intermediate the movable slide members, cam surfaces carried by the movable slide members, stud carrying members having studs engaging said cam surfaces and permitting relative movement between the slides and said stud carrying members during a movement of an underlying leaf outwardly into the plane of the centre leaf, a member adapted to automatically lock together a slide and its co-acting stud carrying member, a movable switch device adapted to throw said locking member to inactive position, and means for actuating said switch device. 95

3. An extension table structure comprising fixed and movable leaves, a central structure connected to the fixed leaf, slides movably mounted at opposite sides of the central structure and connected to the respective movable leaves, roller bars mounted for reciprocation on the central structure, rollers thereon engaging in slots in the slides having horizontal and angular portions, latches to connect the roller bars operatively to the slides, and latch releasing means carried by 110 the slides. 115

4. An extension table structure comprising fixed and movable leaves, a central structure connected to the fixed leaf, slides movably mounted at opposite sides of the central structure and connected to the respective movable leaves, pin bars mounted for reciprocation on the central structure, portions thereon engaging in slots in the slides having horizontal and angular portions, 125 130

latches to connect the pin bars operatively to the slides, and latch releasing means carried by the slides, the latch releasing means comprising strips mounted for reciprocation on the slides and having cam faces to operate the latches, and pawls pivotally mounted to move the releasing strips in one direction; said strips being moved in the opposite direction by engagement with members of the movable leaves.

10 In testimony whereof, I have signed my name to this specification.

JOSEPH COOPER.
